UNITED STATES PATENT OFFICE.

JOHN O. HUNT, OF BROOKLYN, NEW YORK, ASSIGNOR TO INDEPENDENT PAPER MILLS INC., OF BROOKLYN, NEW YORK, A CORPORATION OF NEW YORK.

PAPER FOLDING, CUTTING, AND DELIVERING MACHINE.

Application filed June 21, 1924. Serial No. 721,388.

My present invention relates to an improvement in paper cutting and stacking machines, and more particularly to that type of machines in which a traveling web of 5 paper is cut into predetermined lengths and each successive length of paper as cut from the web is placed in a stack of similar sections cut from the web, and furthermore to that form of apparatus in which each section of the web as cut therefrom may be 10 transversely folded before the same is stacked. The apparatus is particularly adapted for use in the manufacture of paper 15 napkins, towels, toilet paper and similar paper products. In the invention as illustrated, the paper web is preferably folded transversely before being cut and each section of the web as cut therefrom is folded in a position substantially midway its length 20 and then delivered and stacked in a superimposed pile of similar sections of the web. The invention relates still more particularly to the means and the devices for actuating 25 the same for transversely folding and positively gripping each section of the web and the delivery of the same to the stacking devices irrespective of the use to which the apparatus is applied, and also irrespective of the number of traveling webs which may 30 be used at one and the same time and whether or not any or all of such traveling webs are folded transversely or not. A machine embodying my present invention will be hereinafter more particularly described.

35 In the drawing:

Fig. 1 is a side elevation of a machine made in accordance with my present invention.

Fig. 2 is an end elevation of the same.

40 Fig. 3 is a plan.

Fig. 4 is a partial side elevation on an enlarged scale.

Fig. 5 is a sectional end elevation.

Fig. 6 is a partial sectional end elevation 45 showing the gripper devices in a position different to that in which they are illustrated in Fig. 5.

Fig. 7 is a sectional elevation showing the train of driving gears.

50 Fig. 8 is a section and partial elevation of the gripper devices.

Fig. 9 is an end elevation of the same.

Fig. 10 is a plan of the delivery devices.

55 Fig. 11 is an end elevation and partial section of the same.

Fig. 12 is a partial plan of the delivery devices showing a modified form thereof.

Fig. 13 is an elevation of the delivery devices as shown in Fig. 12.

Fig. 14 is an enlarged end elevation of one 60 of the delivery devices illustrating the cams and associated parts for actuating the auxiliary supports for predetermined sections of the paper web in the form of napkins, towels or other articles as the same are delivered by the machine, and 65

Fig. 15 is an elevation illustrating a modification.

As illustrated in the drawing the devices comprising my present invention are mounted 70 in a suitable frame which may include uprights 20, 21, 22, a frame body 23, a transverse member 24, a frame side bracket 25, and oppositely disposed side plates 26 and 27 connected by a tie-bolt 28 or otherwise, it 75 being understood that the other members forming the frame of the apparatus are also suitably connected so as to be secured to one another.

Journaled in bearings provided therefor 80 in the plates 26 and 27, is a drive shaft 29. This drive shaft 29 is suitably coupled to a motor 30 mounted on a motor base 31, and secured in a suitable position preferably above the side plates 26 and 27 there is a 85 starting box and controller 32 for operating the motor. Secured on the drive shaft 29 there is a pinion 33. This pinion 33 meshes with a gear 34 fixed on a shaft 35 suitably journaled in the side plates 26 and 27. Also secured on the shaft 35 is a pinion 36 which meshes with a gear 37 mounted on a shaft 38 also suitably journaled in bearings provided for this purpose in the side plates 26 and 27. The gear 37 meshes with a gear 39 which is fixed on a shaft 40 journaled in 90 bearings provided for this purpose in the side plates 26 and 27. Also meshing with the gear 37 is a gear 41 which is secured to a shaft 42 also journaled in bearings provided therefor in the side plates 26 and 27. This train of gears is preferably mounted 95 on one side of the side plate 26 as clearly illustrated in Figs. 1 to 4 of the drawing. The gears are so arranged that the gear 37 is 100 driven at a speed considerably lower than the motor speed, although the speed at which the gear 37 is driven may be any speed necessary for the proper operation of the machine. The gear 39 is similar to the gear 37

105

110

so that the shaft 40 turns at the same rate as the shaft 38 whereas the relationship between the gears 37 and 41 is such that the shaft 42 turns at twice the speed of the shaft 38. The same relationship maintains between the gear 37 and the gear 36, that is to say the shaft 35 is geared to the shaft 38 so that the former turns at twice the speed of the latter.

10 Mounted on the shaft 35 between the side plates 26 and 27 there is a friction feed roller 43. Mounted on the shaft 38 between the side plates 26 and 27 there is a feed cylinder 44. Similarly mounted on the shaft 40 between the side plates 26 and 27 there is a feed cylinder 45. The friction feed or auxiliary feed roller 43 is preferably made of rubber or is provided with a rubber surface and in a suitable position in the surface of the same there is a transverse groove or notch 46. In the surface of the feed cylinder 44 there are adjacently placed notches 47 and 48 extending across the surface of the same and in the feed cylinder 45 there is transversely placed a knife blade 49 and a pusher plate 50. Mounted on the ends of the feed cylinder 44 there are suitably spaced blocks 51 and 52, the purpose and function of which will be hereinafter described.

30 Also mounted between the side plates 26 and 27 there is a cylinder 53. This is mounted on a shaft 54 journaled in recesses 55 provided therefor in the side plates and adjustably secured in position by nuts 56 or otherwise. Cooperating with this cylinder 53 is a roller 57 carried at the corresponding lower ends of levers 58 which are mounted at their upper ends in a shaft 59 fixed in the side plates 26 and 27 the roller 57 being normally maintained against the surface of the cylinder 53 by the weight thereof and that of the arms 58 through the action of gravity.

15 Mounted on the shaft 42 between the side plates 26 and 27 there is a creaser cylinder 60. In the periphery of this creaser cylinder there are suitably spaced circumferential grooves 61 and 62. This creaser cylinder is also provided with a longitudinal groove 63. At the ends of this cylinder the same is provided with recesses 64 and 65. Also mounted on the shaft 42 and between the ends of the cylinder 60 in the adjacent inner faces of the side plates 26 and 27 there are rocker plates 66 and 67. These rocker plates are suitably connected to bearing sleeves 68 and 69 respectively which are journaled on the said shaft 42 so that these rocker plates turn on the shaft. In the longitudinal groove 63 in the surface of the cylinder 60 there is a clamp or gripper bar 70. The opposite ends of this gripper bar are shouldered as indicated at 71 and 72 respectively and the extremities of the gripper bar extend into recesses 73 and 74 provided therefor in the rocker plates 66 and 67. At one end of the

cylinder there is a pin 75, and in a similar position at the opposite end of the cylinder there is a pin 76. These pins at corresponding ends are suitably secured in the body of the cylinder. Both pins are adapted at 70 their outer ends to lie in the recesses 64 and 65 and are provided with springs 77 and 78 which extend from collars 79 and 80, against which corresponding ends of the springs are adapted to bear, to the said clamp bar 70 so as to normally maintain one face of the clamp bar 70 in contact with the adjacent face defining one side wall of the longitudinal groove 63 in the surface of the cylinder 60, thus, as will be understood, maintaining the rocker plates 66 and 67 in a predetermined position relatively to the cylinder. As indicated particularly in Figs. 5 and 9, the adjacent normally abutting faces of the clamp bar 70 and the wall defining the recess 63 are provided with grooves 81 and 82. In the cylinder 44 in a position diametrically opposite that in which the notches 47 and 48 are placed there is a pusher bar 83 which cooperates with the grooves 81 and 82, as will be hereinafter more particularly described.

25 Associated with the feed cylinder 44 there are stripper rods 84 and 85. These stripper rods are suitably connected to collars 86 and 87 respectively both mounted on a shaft 88. These stripper rods at their free ends enter circumferential grooves 89 and 90 respectively provided in the feed roll 44 for the purpose of directing the folded paper from the surface of the roll or cylinder, as will be hereinafter more particularly described.

35 Associated with the creaser cylinder 60 is an auxiliary creaser cylinder 91. This cylinder 91 is mounted on stub shafts 92 and 93 connected respectively to brackets 94 and 95 which are secured in any suitable manner to the frame of the machine. Extending into these grooves 61 and 62 in the creaser roll 60 so that the extremities thereof lie between the creaser cylinder 60 and its auxiliary cylinder 91 there are stripper rods 98 and 99 which are carried by a plate 100, secured to the frame of the machine in any suitable manner.

40 From the foregoing it will be understood that the feed cylinders 44 and 45 also act as cutter cylinders and that the creaser cylinders 60 and 91 also act as delivery cylinders.

45 The devices for receiving and piling the folded sheets of paper comprising towels, napkins or other articles into stacks of predetermined number may as illustrated include a shaft 101 mounted in bearings 102 and 103 extending transversely of the cylinder shafts as hereinbefore described and at one end of these cylinders and below the same. At the other end of the cylinders and in a similar position there is a corresponding transverse

50 75 80 85 90 95 100 105 110 115 120 125 130 135

shaft 103 mounted in bearings 104 suitably secured to the frame of the machine. Both these shafts are driven from the shaft 42. On the shaft 42 there is a worm 105 and on the shaft 101 a worm gear 106. Similarly on the shaft 42 there is a worm 107 and on the shaft 103 a worm gear 108. The shafts 101 and 103 are driven in opposite directions and as viewed in Fig. 10, for example, 10 the shaft 101 revolves in a clockwise direction and the shaft 103 in a counterclockwise direction. These shafts extend an appreciable distance beyond the frame of the machine and carry devices for receiving the 15 sheets of folded paper as the same are delivered by the machine.

On the shaft 101 there is a drum 109. Secured in the surface of this drum and extending longitudinally thereof there is a series of receiver blades 110. As illustrated 20 the apparatus is designed to deliver 10 folded sheets with each revolution of the drum and for this reason there are 10 equally spaced receiver blades fixed longitudinally in the drum. Each of these blades is divided into sections leaving spaces 111 and 112 in predetermined positions between the adjacent ends of the sections of each blade. At the inner end of each blade the same is 25 bent or curved as indicated at 113 in a direction in advance of the direction in which the drum is adapted to revolve in order to insure the entry of a folded sheet between adjacent support blades in the operation of the 30 apparatus, as will also be hereinafter more particularly described. Similarly on the shaft 103 there is mounted a drum 104 in the periphery of which there is secured a corresponding series of support blades 115. 35 Each of these blades 115 is composed of sections spaced at suitable intervals as indicated at 116 and 117, these spaces corresponding, of course, with the similar spaces in the complementary support blades of the drum 40 109. Also at their inner ends each of these support blades 115 is bent or curved in the direction corresponding to the direction in which the drum revolves, the curved ends of the blades 115 being designated at 118.

Adjacent the outer end of the drum 109 there is a disk 119 against which the adjacent ends of the support blades bear, and similarly at the outer end of the drum 114 there is a disk 120 contacting with the adjacent ends of the support blades 115. On 45 the shaft 101 there is a collar 121 and on the shaft 103 there is a similar collar 122. As will be understood, the disk 119 may be integral with the collar 121 and the disk 120 integral with the collar 122 or otherwise, and the disks serve as stops to limit the outward movement of the folded sheets as they are delivered from the delivery rolls or cylinders to the support blades 110 and 115 carried by the drums 109 and 114. The collar 50 121 is provided with a radially placed pin 123.

Support blocks 124 and 125 are suitably secured to the frame of the machine and extend beneath the drums 109 and 114. Connected to the support block 124 there are brackets 126, and similarly connected to the support block 125 there are brackets 127. In each bracket 126 there is fixed a vertical guide bar. As illustrated and inasmuch as 55 there are two divisions in the support blades there are two brackets 126, in one of which one guide bar 128 is fixed and in the other of which a guide bar 129 is fixed. Similarly beneath the drum 109 there are two brackets 127. In one of these a guide bar 130 is fixed and in the other a guide bar 131 is fixed. The brackets 126 are so placed that the guide bar 128 extends upwardly and its upper extremity lies within the space 116 and the 60 guide bar 129 extends upwardly with its extremity lying within the space 117. In the same manner the brackets 127 are so placed that the guide bar 130 extends upwardly and its upper extremity lies within the space 111 and the guide bar 131 extends upwardly and its extremity lies within the space 112. The oppositely disposed guide bars, namely 65 128 and 130, and 129 and 131 are so spaced from each other as to be of approximately 70 the same width as the folded strip of paper delivered from the machine to the support blades and from the support blades to the temporary support as hereinafter described.

Mounted in the brackets 127 and extending through the guide bars 130 and 131 is a rocker shaft 132. Fixed in this rocker shaft is a series of support arms 133. These are 75 suitably spaced and of any desired number and each at its end is preferably upturned as indicated at 134. The rocker shaft 132 and the support arms carried thereby are normally maintained in position and when moved returned to this position by a spring 80 135 surrounding a portion of the rocker shaft. Similarly in the other side of the machine there is a corresponding rocker shaft 136 which is mounted in the brackets 126 and extends through the guide bars 128 and 129. Fixed in this rocker shaft 136 there is a corresponding number of support arms 137 each of which at its outer end is 85 upturned as indicated at 138. The rocker shaft 136 and the support arms carried thereby are normally maintained in position 90 and when moved returned thereto by a spring 139 surrounding a portion of this rocker shaft. At the inner end of the rocker shaft 132 there is a collar 140 carrying a crank arm 141 and at the inner end of the 95 rocker shaft 136 there is a collar 142 carrying a crank arm 143. The crank arm 141 is connected to the crank arm 143 by a link 144 and as indicated these parts may be normally maintained in an initial position 100 130

through the actions of the springs 135 and 139 by stops 145 against which the corresponding ends of the support arms 137 may be brought to bear.

5 In order to operate the support arms 133 and 137 and to determine the number of folded sheets as napkins, towels or other articles which are piled in stacks each of predetermined number, I may employ a suitably mounted stub shaft 146 fitted with a removable head 147 and an inner hub 148 and an outer hub 149, these parts being maintained in their relative positions by means of a spring 150 or otherwise. The inner hub 148 is provided with a series of radially placed pins 151 and the outer hub 149 with a similarly placed series of pins 152. The pin 123 secured in the collar 121 as hereinbefore described is adapted to contact with each of the pins 152 in the outer hub 149 and in a suitable position in the outer face of the disk 119 there is a block 153 adapted to contact with the pins 151 on the inner hub 148. At the outer end of the rocker shaft 132 there is a trip lever 155, and on one of the pins 152 there is a trip pin 154 adapted to engage with the trip lever 155. As illustrated the drums 109 and 114 are both provided with ten support blades so that 10 folded sheets or napkins or towels are delivered with each revolution of these drums. The inner hub 148 is provided with five radial pins 151 and the outer hub 149 with five radial pins 152 so that when the pin 123 contacts with one of the pins 152 the inner and outer hubs are moved a tenth of a revolution and when the block 153 contacts with one of the pins 151 the inner and outer hubs are moved another tenth of a revolution so that with each revolution of the drums 109 and 114 the inner and outer heads are moved a fifth of a revolution. The pin 154 contacts with the trip lever 155 once in each complete revolution of the inner and outer hubs and in so doing swings the rocker shafts and the support arms carried thereby from the full line to the dotted line positions in Fig. 11 of the drawing to drop 50 of the folded sheets which are delivered to the upturned ends of the support arms with every five revolutions of the drums 109 and 114. It will be understood that this arrangement is only diagrammatic and that the apparatus may be readily changed to deliver any other predetermined number of folded sheets as may be desired.

60 In order in some instances to prevent one or more of the folded sheets from missing the support arms in the event of the support arms not returning to their initial positions in time to receive the next succeeding sheet after having delivered a stack of the sheets, it may be advisable to employ auxiliary support arms such, for example, as illustrated 55 in Figs. 12, 13 and 14. To this end as shown in these figures of the drawing the drum 109 may be fitted with a rocker shaft 156 in which auxiliary support arms 157 are secured, the rocker shaft and its support arms being yieldingly maintained in an initial position by the action of a spring 158. Similarly in the drum 114 there is a rocker shaft 159. This is fitted with auxiliary support arms 160 oppositely disposed to the auxiliary support arms 157. The 70 rocker shaft 159 and its auxiliary support arms 160 are normally maintained in an initial position by the action of a spring 161. In this structure there is a front plate 162 extending between the shafts 101 and 80 103 and lying immediately behind the disks 163 and 164 which correspond to the disks 119 and 120. At the rear or inner side of the front plate 162 there are spacer plates 165 and 166. The rocker shaft 156 and 85 its auxiliary support arms 157 are actuated through suitable crank arms and cams. As illustrated, for this purpose there is an outer cam 167 and an inner cam 168, while at the end of the rocker shaft 156 there is a 90 bell crank 169 provided with suitable pins on which rollers 170 and 171 are mounted. These are clearly illustrated in Fig. 14 of the drawing. The rocker shaft 159 and its auxiliary support arms 160 are operated in 95 the same manner by similar cams placed in the reverse positions. The outer cam for this purpose is indicated at 172 and the inner cam at 173, while the bell crank at the end of the rocker shaft 159 is indicated at 100 174 and the rollers for contacting with the faces of the cams are indicated at 175 and 176. The roller 170 is adapted to bear against the face of the cam 167 and the roller 171 against the face of the cam 168. Similarly the roller 175 is adapted to bear against the face of the cam 172 and the roller 176 against the face of the cam 173. The faces of these cams are so shaped that when the auxiliary support arms are in a juxtaposed 105 position between the drums they are substantially horizontal and continue to assume a substantially horizontal position for a continued portion of the revolution of the drums, at the same time receding from 110 each other so as to receive a folded strip of paper as the same is delivered from the machine and to support the same until the support arms 133 and 137 have returned to their initial position to perform the function of supporting these folded sheets of paper as the same come from the machine and are fed to and delivered by the support blades 110 and 115, it being understood that when the rollers 170 and 175 run off 115 the faces of the cams 167 and 172 the rollers 171 and 176 engage the faces of the cams 168 and 173 and in so doing shift the rocker shafts to such positions that the auxiliary support arms are out of the way of 120 125 130

other operative parts of the mechanism. It will also be understood that these auxiliary support arms thus come into play to receive every tenth sheet of the folded web of paper, 5 that is to say every tenth paper napkin, towel or similar article. As the articles piled in stacks of predetermined numbers are dropped by the support arms 133 and 137 they are guided in their descent by the 10 guide bars 128, 129, 130 and 131 and fall upon a platform 177 mounted beneath the same and supported by a bracket 178 suitably fixed in the frame of the machine. From this platform, as will be understood, 15 each pile of superimposed sheets may be suitably removed and bundled.

As shown a traveling paper web is folded longitudinally into a predetermined number of sections as may be required by any suitable apparatus, such for example as shown 20 and described in my copending application, Serial No. 682,450, filed December 24, 1923, for a paper folding machine. This paper folding machine comprises complementary 25 members for longitudinally folding the paper, one of which is fixed and the other adjustable to position relatively thereto. As shown in the drawing the fixed member of this longitudinal folding device as indicated 30 at 179 may be secured in the frame of the machine by a bracket or other support 180 and the movable member 181 may be supported on a slidable base 182 which when adjusted to the desired position may be fixed 35 therein by a set screw 183 or otherwise. The paper to be folded is supplied from a reel as indicated at 184 and passes over a suitably mounted idler 185 and over the rollers 186 forming part of the devices for longitudinally folding the web.

In order to prevent the paper from feeding too rapidly and also to prevent the momentum of the reel from feeding the paper after the machine is stopped and before the 45 same is started again, for example, it may be advisable in some instances to provide a positive feed for the paper as the same is unwound from the reel. To this end the trunnions 187 of the reel are passed between the sides 188 of yoke members carried by 50 brackets 189 so that the reel 184 may rest upon a cylinder 190 mounted on a shaft 191 journaled in the brackets. The ends of the cylinder 190 are provided with flanges 192 between which the reel of paper passes so 55 that the flanges assist in guiding the paper as the same is unwound from the reel. The brackets 189 are connected by a tie-bolt 193. The shaft 191 and the cylinder 190 mounted thereon are positively driven from the shaft 60 58. On the shaft 191 there is a gear 194 meshing with a gear 195 on a vertical shaft 196. At the opposite end of the vertical shaft 196 there is a gear 197 meshing with a gear 198 on a shaft 199 which is connected

by a coupling 200 or otherwise to a shaft 201 suitably connected to the shaft 38, at the opposite end of which at the side of the machine there is a handle 202 by which when necessary when the power is disconnected 70 the revolving parts of the apparatus may be turned over. It will be understood that the reel 184 will therefore be turned positively and the paper correspondingly fed therefrom although the speed at which the reel is turned is not sufficient to entirely feed the paper so that there is a predetermined degree of slip between the surface of the cylinder 190 in order of course that the paper as supplied to the folder is under the 80 necessary tension.

In the operation of the apparatus the paper web indicated at 203 is fed from the reel 184 through the members 179 and 181 of the folder device, such for example as 85 shown and described in my copending application Serial No. 682,450, as aforesaid to fold the web longitudinally, that is in the direction in which it travels into a plurality of sections. The web thus folded as indicated at 204 passes between the cylinder 53 and the roller 57 and then between the cylinder 44 and the feed roller 43, thence between the feed cylinder 44 and the feed cylinder 45. With each revolution of the cylinders 44 and 45 the knife blade 49 enters the notch 47 and cuts a strip of predetermined length from the traveling web. The length of this strip is approximately the circumference of the cylinder 44. After the web is thus cut 95 the pusher or insertion plate 50 engages the free end of the advancing web and insures the same being properly fed between the shearer feed cylinder 44 and the knife feed cylinder. As these cylinders continue to revolve the strip cut from the web passes between the feed cylinder 44 and the delivery cylinder 60. When the feed cylinder 44 has turned approximately a half revolution the pusher or insertion bar 83 after having 100 passed the feed cylinder 45 by entering the notch 83' therein engages the paper strip midway of its length and forces the same from the surface of the feed cylinder 44. It will be understood that the forward end of the strip of material after passing between the feed cylinder 44 and the delivery cylinder 60 is freed from the surface of the feed cylinder 44 by the stripper rods 84 and 85. As the cylinders 44 and 60 continue to revolve the projections 205 on the rocker plates 66 and 67 come into contact with the blocks 52 and because of the fact that the surface speeds of cylinders 60 and 44 110 are the same and projections 205 extend beyond the surface of cylinder 60 while blocks 52 stop short of the surface of cylinder 44, the revoluble motion of the rocker plates 66 and 67 is retarded relatively to 115 the cylinder 60 against the action of the 120 cylinder 44.

springs 77 and 78 and this action also retards the motion of the clamp bar 70 causing an opening between the same and the face defining the adjacent wall of the groove 63 for the entrance of the pusher or insertion bar 83 and the central portion of the strip of the web. In the continued revolution of the cylinders 44 and 60 the edge of the pusher or insertion bar first coacts with the recess 82 and as will be understood as the cylinders continue to revolve the pusher or insertion bar 83 is withdrawn from the groove and in doing so operates in the recess 81 and as the projections 205 move off the blocks 52 the actions of the springs 77 and 78 return the clamp bar and the rocker plates to their initial positions whereby this central transverse portion of the section of the web is gripped between the clamp bar and the adjacent wall defining the recess 63. The central portion of the section of the web thus transversely gripped is carried by the continued revolution of the cylinder 60 until the projections 206 on the rocker plates 63 and 67 come into contact with the blocks 51. Just prior to the time when the transversely folded edge of the section of the web passes under the stripper rods 98 and 99, the extremities 206 of the rocker plates 63 and 67 come into contact with the blocks 51 and again retard the revoluble motion of the rocker plates relatively to the delivery cylinder 60 and correspondingly retard the movement of the clamp bar 70 against the actions of the spring 77 and 78 to release the folded edge of the section of the paper web to permit the same to pass beneath the ends of the stripper rods and between the delivery cylinder 60 and the auxiliary delivery cylinder 91.

Each transversely folded section of the web is then passed by the delivery cylinder 60 and the auxiliary cylinder 91 between adjacent support blades 110 and 115 on the revolving drums 109 and 114, each succeeding section of the paper web being supported upon the lower set of support blades and delivered thereby to the upturned ends 134 and 138 of the support arms 133 and 137 after having been suitably positioned by the guide bars 128, 129, 130 and 131. It will be understood that the parts are timed in such a manner that the successive transversely folded sections of the web as they come from the delivery cylinder and the auxiliary delivery cylinder pass between the succeeding sets of support blades 110 and 115, the inner ends of these support blades being turned in the direction of the rotation of the drums to which they are connected to facilitate and make this action certain. As the sections of folded web accumulate on the upturned ends 134 and 138 of the support arms the weight of the same may depress the support arms against the actions of the springs 135 and 139 and when a predetermined number of the transversely folded sections of the web are delivered to the support arms the rocker shafts 132 and 136 are actuated through the tripper mechanism to permit a predetermined number of articles to fall to the platform, being directed thereto by the guide bars 128, 129, 130 and 131. As illustrated, and as hereinbefore described there are ten sets of the support blades 110 and 115 so that ten articles are delivered with each revolution of the drums 109 and 114, and as the tripper mechanism is set to operate once in every five revolutions of the drums there will be fifty transversely folded sections of the web or articles piled in each stack as the same are permitted to fall to the platform. As hereinbefore stated, however, this number is only illustrative as the apparatus may be constructed and set to pile any predetermined number of the articles in each stack.

Also as hereinbefore described in some instances it may be advisable to employ the auxiliary support arms 157 and 160 which are operated by the cams and associated parts as hereinbefore described to bring the auxiliary support arms into operative position once in each revolution of the drums 109 and 114 so as to receive each tenth transversely folded section of the strip to support the same and succeeding folded sections of the strip until the support arms 133 and 137 are returned to their initial positions when the folded sections of the web are delivered by the auxiliary support arms 157 and 160 to the upturned ends 134 and 138 of the main support arms 133 and 137. It will furthermore be understood that the superimposed piles of transversely folded sections of the web comprising paper napkins, towels or other articles stacked in predetermined numbers as hereinbefore described may be suitably conveyed from the platform to which they are delivered and wrapped by another mechanism or placed in a suitable container by devices which form no part of my present invention.

It is to be noted that the apparatus as herein shown and described is designed to transversely fold and stack paper napkins folded in a predetermined manner, that is to say the web from which the napkins are made is first longitudinally folded and then predetermined sections of the web cut therefrom and each web section folded transversely and delivered and stacked by the machine. For this reason the pusher bar 83 carried by the cylinder 44 is placed in a position diametrically opposite the notches 47 and 48. This pusher bar 83 as will be readily understood may be placed in any desired position on the cylinder 44 depending upon the character of the work to be done by the machine. For example, in instances

where it is not necessary to fold the sections as cut from the web, as in toilet paper, the pusher bar may be placed between the notches 47 and 48 whereby the end of the 5 traveling web whether folded or otherwise is forced into the grooves 81 and 82 and the sections of the web are successively fed endwise to the delivery cylinder. Obviously 10 also this pusher bar may be placed at any desired angle instead of extending longitudinally across the cylinder 44.

As herein shown and described, particular reference being made to Figs. 5 and 6, it will be noted that the contact blocks 51 and 15 52 are placed in a position within the circumference of the cylinder 44, the radius of the same, therefore, being less than that of the cylinder while the projections 205 and 206 of the rocker plates extend beyond the 20 surface of the delivery cylinder 60 and the length of the contact arms formed by these projections is therefore greater than the radius of the cylinder 60. As the peripheral speed of the cylinders 44 and 60 is the same 25 the blocks, as hereinbefore described, retard the rocker links while the springs 77 and 78 tend to advance the same and to maintain them in an initially normal position. It will be apparent that these conditions 30 may be reversed and the same results obtained, that is to say the blocks 51 and 52 may be extended beyond the periphery of the cylinder 44 so that the radius of the contact points is greater than the radius of the cylinder 44 and the projections 205 and 206 of the rocker plates may be shortened 35 so as to lie within the periphery of the delivery cylinder 60 making the radius of the same less than that of the cylinder 60. This 40 obviously will reverse the action hereinbefore described, but obviously will produce the same result. Other equal and obvious changes may be made in the apparatus to accommodate the same to various working 45 conditions without departing from the nature and spirit of my invention.

In some instances, particularly in cutting and stacking sections of a paper web which has been longitudinally folded to provide 50 an outermost portion which is narrower than the folded web, and under certain atmospheric conditions the static electricity may be sufficient to cause these narrower sections of the articles to be displaced either moving 55 outwardly or otherwise and to prevent the articles from nesting properly while being stacked. To overcome this difficulty I may employ a pneumatic device to maintain these narrower sections of the folded article in 60 position while being stacked. As illustrated in Fig. 15 for this purpose I may employ a pipe 203 secured in the machine and projecting downwardly at a predetermined angle immediately above and between the 65 drums 109 and 114 and the blades 110 and

115 carried thereby respectively. Along the bottom of this pipe 203 there is a series of spaced apertures 204 and by a blower or any other similar device the draft of air is forced to and through the pipe, being admitted downwardly through the openings therein against the central portion of each of the sections of the web as it is delivered to the said blades in order, as hereinbefore stated, to maintain the central portions of 70 75 the folded sections of the web in position to assist in properly nesting the same while they are being stacked.

I claim as my invention:

1. In a paper feeding, cutting and delivering machine, cylinders for moving a paper web longitudinally and cutting the same into sections of predetermined length, a knife carried by one cylinder to cooperate with a groove in another cylinder for transversely cutting the paper web, a pusher plate carried by the cylinder carrying the knife, the said pusher plate cooperating with another groove in the other cylinder for engaging and directing the adjacent end of the web after a section has been cut therefrom into the said other groove to insure the continued movement of the forward end of the web into engagement with the said cylinders, and a web folding device associated with one 90 95 of said cylinders.

2. In a paper feeding, cutting and delivering machine, a plurality of cylinders comprising a main feed cylinder, an auxiliary feed cylinder and a knife cylinder for moving a paper web longitudinally and cutting the same transversely into sections of predetermined length, a knife blade carried by the said knife cylinder and cooperating with a groove in the said main cylinder for cutting the web transversely each time the said cylinders revolve, a pusher plate connected to the said knife cylinder in a position adjacent the said knife blade and cooperating with a second groove in the main 105 cylinder for engaging the adjacent end of the paper web after a section has been cut therefrom to continue the movement of the end of the web and to insure its engagement between the said knife and main cylinders, 110 115 and a web folding device associated with one of said cylinders.

3. In a paper feeding, cutting and delivering machine, cylinders for moving and cutting a paper web into sections of predetermined length, delivery cylinders, a clamp device associated with one of the delivery cylinders, means for operating the clamp device from one of said cylinders for moving and cutting the web, and a device 120 125 also associated with one of the cylinders for moving the web for engaging each web section and inserting the same into the said clamp device.

4. In a paper feeding, cutting and deliver- 130

ing machine, cylinders for moving and cutting a paper web into sections of predetermined length, delivery cylinders, a clamp device carried by one of the delivery cylinders, means for operating the clamp device from one of said cylinders for moving and cutting the web, and a device also carried by one of the cylinders for moving the web for engaging each section of the web in a substantially central transverse position and inserting that portion of the web so engaged into the said clamp device.

5. In a paper feeding, cutting and delivering machine, cylinders for moving and cutting

15 tting a paper web into sections of predetermined length, a delivery cylinder having a longitudinal groove in the face thereof, a clamp bar lying within the said groove, means for normally maintaining the clamp
20 bar in an initial position, with one face thereof against the wall defining the adjacent side of the said groove, means for operating the said clamp bar from one of said cylinders for moving and cutting the web,
25 and means also carried by one of the cylinders for moving the web for engaging each section of the web transversely substantially midway of its length and moving the portion of the web so engaged into the said
30 groove in the delivery cylinder so as to be engaged by the clamp bar.

35 6. In a paper feeding, cutting and delivering machine, cylinders for moving and cutting a paper web into sections of predetermined length, a delivery cylinder having a longitudinal groove in the surface thereof, a clamp bar lying within the said groove, rocker plates at the ends of the delivery cylinder and into which the extremities of the 40 clamp bar pass, means for normally maintaining the said clamp bar and rocker plates in position relatively to the said delivery cylinder, means carried by one of the cylinders for moving the web for engaging the 45 said rocker plates for operating the clamp bar, and a device also carried by one of the said cylinders for moving the web for engaging each section of the web transversely substantially midway of its length and inserting that portion of the web so engaged into the groove in the delivery cylinder so that the same may be engaged by the clamp bar.

50

7. In a paper feeding, cutting and delivering machine, cylinders for moving and cutting a paper web into sections of predetermined length, a delivery cylinder having a longitudinal groove in the surface thereof, a clamp bar lying within the said groove, rocker plates at the ends of the delivery cylinder and into which the extremities of the clamp bar pass, means for normally maintaining the said clamp bar and rocker plates in position relatively to the said delivery cylinder, means carried by one of the cylinders for moving the web for engaging

the said rocker plates for operating the clamp bar, a device also carried by one of the said cylinders for moving the web for engaging each section of the web transversely substantially midway of its length 70 and inserting that portion of the web so engaged into the groove in the delivery cylinder so that the same may be engaged by the clamp bar, and a second means also carried by one of the cylinders for moving the web for engaging the said rocker plates to again operate the clamp bar to release the central transverse portion of a section of the paper web. 75

8. In a paper feeding, cutting and delivering machine, cylinders for moving and cutting a paper web into sections of predetermined length, a shaft, a delivery cylinder mounted on the said shaft and having a longitudinal groove in the surface thereof, rocker plates revoluble on the said shaft at the ends of the said delivery cylinder, a clamp bar lying in the longitudinal groove in the delivery cylinder and extending through the said rocker plates, spring devices for normally maintaining the said rocker plates in position relatively to the said delivery cylinder in which position the clamp bar bears against the wall defining the adjacent face of the said groove in the delivery cylinder, means carried by one of the cylinders for moving the paper web for engaging the said rocker plates to retard the movement thereof relatively to the movement of the delivery cylinder to operate the said clamp bar, and a device also carried by one of the cylinders for removing the paper web and adapted to transversely engage each section of the paper web midway of its length and to insert the same into the said longitudinal groove in the surface of the delivery cylinder to be engaged and released by the said clamp bar.

9. In a paper feeding, cutting and delivering machine, cylinders for moving and cutting a paper web into sections of predetermined length, a shaft, a delivery cylinder mounted on the said shaft and having a longitudinal groove in the surface thereof, rocker plates revoluble on the said shaft at the ends of the said delivery cylinder, a clamp bar lying in the longitudinal groove in the delivery cylinder and extending through the said rocker plates, spring devices for normally maintaining the said rocker plates in position relatively to the said delivery cylinder in which position the clamp bar bears against the wall defining the adjacent face of the said groove in the delivery cylinder, blocks carried by one of the cylinders for moving a paper web for engaging the said rocker plates to retard the relative movement between the same and the said delivery cylinder and to thereby shift the position of the said clamp bar in the groove 130

- in the cylinder, and a device also carried by one of the cylinders for moving the web for transversely engaging each section of the web substantially midway of its length and 5 inserting that portion of the web so engaged into the groove in the delivery cylinder so as to be engaged and released by the said clamp bar therein.
10. In a paper feeding, cutting and delivering machine, cylinders for moving and cutting a paper web into sections of predetermined length, a shaft, a delivery cylinder mounted on the said shaft and having a longitudinal groove in the surface thereof, 10 rocker plates revoluble on the said shaft at the ends of the said delivery cylinder, a clamp bar lying in the longitudinal groove in the delivery cylinder and extending through the said rocker plates, spring devices for normally maintaining the said 15 rocker plates in position relatively to the said delivery cylinder in which position the clamp bar bears against the wall defining the adjacent face of the said groove in the 20 delivery cylinder, blocks carried by one of the cylinders for moving a paper web for engaging the said rocker plates to retard the relative movement between the same and the said delivery cylinder and to thereby shift 25 the position of the said clamp bar in the groove in the cylinder, and an insertion plate carried by one of the cylinders for removing the paper web for engaging each section of the web transversely thereof substantially 30 midway of its length for inserting that portion of each section of the web so engaged into the groove in the delivery cylinder for being engaged with and released by the said clamp bar therein.
- 35 11. In a paper feeding, cutting and delivering machine, a set of cylinders for moving and cutting a paper web into sections of predetermined length, a shaft, a delivery cylinder mounted on the shaft and having a longitudinal groove in the surface thereof, 40 rocker plates mounted on the shaft at the ends of the said delivery cylinder, a clamp bar located within the said groove and extending through the said rocker plates, tension devices for normally maintaining the 45 rocker plates in position relatively to the delivery cylinder in which the said clamp bar bears against the adjacent face defining the wall of the said groove, the said rocker plates being provided with sets of projections, devices on one of the cylinders for moving the paper web for engaging one set of projections on the rocker plates to move the said clamp bar relatively to the delivery cylinder, 50 similar devices also on the same cylinder for moving the paper web for engaging the other set of projections on the rocker plates to move the clamp bar a second time relatively to the delivery cylinder for each 55 revolution of the said cylinder for releasing the paper web, and an insertion plate also carried by one of the cylinders for moving the paper web for engaging each section of the web transversely substantially midway of its length to insert that portion of the 60 section of the web so engaged in the groove in the delivery cylinder the first time the clamp bar is moved to be engaged by the clamp bar when released, the portion of the web so engaged being released when the clamp bar is moved the second time by the 65 said engagement of the second set of projections on the rocker plates with the second set of devices on the said cylinder.
- 70 12. In a paper feeding, cutting and delivering machine, a set of cylinders for moving and cutting a paper web into sections of predetermined length, a shaft, a delivery cylinder, 75 mounted on the shaft and having a longitudinal groove in the surface thereof, rocker plates mounted on the shaft at the ends of the said delivery cylinder, a clamp bar located within the said groove and extending through the said rocker plates, tension devices for normally maintaining the 80 rocker plates in position relatively to the delivery cylinder in which the said clamp bar bears against the adjacent face defining the wall of the said groove, the said rocker plates being provided with sets of projections, devices on one of the cylinders for moving the paper web for engaging one set of projections on the rocker plates to move the said clamp bar relatively to the delivery cylinder, 85 similar devices also on the same cylinder for moving the paper web for engaging the other set of projections on the rocker plates to move the clamp bar a second time relatively to the delivery cylinder for each 90 revolution of the said cylinder for releasing the paper web, and an insertion plate also carried by one of the cylinders for moving the paper web for engaging each section of the web transversely substantially midway of its length to insert that portion of the section of the web so engaged in the groove in the delivery cylinder the first time the clamp bar is moved to be engaged by the clamp bar when released, the portion of the web so engaged being released when the clamp bar is moved the second time by the 95 said engagement of the second set of projections on the rocker plates with the second set of devices on the said cylinder.
- 100 13. In a paper feeding, cutting and delivering machine, cylinders for moving and cutting a paper web into sections of predetermined length, delivery cylinders, a clamp device carried by one of the delivery cylinders, means for operating the clamp device from one of said cylinders for moving and cutting the web, and a device also carried by one of the cylinders for moving the web for engaging each section of the web in a transverse position and inserting that por- 105

tion of the web so engaged into the said clamp device.

14. In a paper feeding, cutting and delivering machine, cylinders for moving and cutting a paper web into sections of predetermined length, a delivery cylinder having a longitudinal groove in the face thereof, a clamp bar lying within the said groove, means for normally maintaining the clamp bar in an initial position, with one face thereof against the wall defining the adja-

cent side of the said groove, means for operating the said clamp bar from one of said cylinders for moving and cutting the web, and means also carried by one of the cylinders for moving the web for engaging each section of the web transversely and moving the portion of the web so engaged into the said groove in the delivery cylinder so as to be engaged by the clamp bar. ¹⁵

Signed by me this 13th day of June, 1924.

JOHN O. HUNT. ²⁰
